UNITED STATES PATENT OFFICE.

ULRICH KLOSS, OF BERLIN, GERMANY.

D. C. RAILWAY SYSTEM.

Application filed March 22, 1928, Serial No. 263,729, and in Germany June 14, 1927.

This invention relates to electric railway systems, and is applicable to all systems in which a vehicle is propelled electrically over the rails and in which the track, as regards the supply of current, is divided into zones or sections which are each supplied with current separately. The term "railway" is accordingly intended to apply in its broader sense to also cover other rail systems, such as tramway systems, although for better comprehension the invention will be described with reference to a "railway" in its usually accepted meaning.

More particularly, the invention relates to a method of disconnecting at a distance a certain zone or zones in the case of D. C. railway systems, that is to say depriving such zone or zones of current. This disconnection may be performed either from the train itself or from the block sections. In case of danger, for example a fire on the train, it is necessary to switch off the voltage on the train itself. For this purpose it has hitherto been usual to employ short-circuiting devices which, however, are associated with various disadvantages. The short-circuiting system, due to the great strengths of current, which are compensated, constitutes a source of extreme danger to the operator. If a number of sub-stations coupled together supply current to the zone which it is desired to disconnect, and in addition both directions of travel, i. e., the up and down rails, are connected by means of automatic devices, unnecessarily large zones, and in particular also the opposite direction track, will be deprived of current by the short-circuiting. It may also occur that in the case of relatively long feed stretches the automatic devices are not released, as the resistance of the circuit formed by the contact rail and the travelling rail is so great that the releasing current strength is not attained. If short-circuiting is effected in the vicinity of a sub-station, this in many cases will lead to considerable damage to the switch apparatus and machines. In the case of rotary rectifiers flashing-over occurs and the rectifiers tend towards backfiring, whereby the track may be rendered unusable for a considerable length of time.

Now it is the object of the invention to overcome the disadvantages referred to, and this in accordance with the invention is accomplished by the fact that actuation as desired of a device provided on the train, or at

the block sections respectively, compels the sub-station to supply intermittent D. C. in the feed circuit, this intermittent D. C., with the assistance of a transformer and a time relay, serving to release one or more automatic devices on the track.

According to the invention, a transformer (inductance coil) is employed, the primary coil of which is connected in series with the contact rail lead, while the secondary coil is connected to the time relay, which by the use of a local battery or the like actuates the automatic device on the track. For the purpose of forming a circuit with intermittent D. C., which is superposed to the main D. C. circuit, a make and break device is employed, which is operated manually or by means of a motor, and possesses a low periodicity, the same being mounted on the train or at a block section. This make and break device is connected between contact rail and travelling rail, i. e., is in series with the collecting bar of the sub-station. Each coupling station and each sub-station are furnished with a transformer and a time relay acting on the corresponding track automatic device. The different time relays are set in such manner that at first the time relay of the coupling station responds and the longitudinal and cross coupling arrested, so that in this manner the error is localized to the one zone to be disconnected. Not until then does the time relay move into function, the same then acting on the feed switch of the sub-station. Due to the inductance of the rails, it is desirable to select the periodicity of the intermittent D. C. at, say, 10-20.

The invention will now be described more fully with reference to the accompanying drawing, in which a form of embodiment by way of example is shown in diagrammatical form.

Fig. 1 is a diagram of connections pertaining to the sub-station.

Fig. 2 is a diagrammatic representation of the make and break device for generating the intermittent D. C.

Fig. 3 is a diagram of connections for a double-line track with sub-stations and a coupling station.

Referring to the drawing, 1 is the dynamo of the D. C. power station, or the converter of a sub-station respectively, which converter through the medium of the automatic device 2 and the track automatic device 3 serves to

supply current to the contact rail 4, whereby the other pole of the dynamo is connected in the usual manner through the collecting bar 5 to the travelling rail 6. Between the 5 track automatic device 3 and the contact rail 4 is a transformer (inductance) comprising a primary winding 7 and a secondary winding 8. The primary winding 7 is connected in series with the dynamo 1, while the secondary winding 8 is connected to a time relay 10 and 11 to be connected. The strength of the intermittent D. C. is somewhere in the neighborhood of 25 amp, as compared with releasing currents of 3,500-5,000 amp, for each automatic device. The same may be applied to practically any desired distance. In 70 place of operation by the electro-motor 19, a hand-operating means with crank or the like may be employed for the make and break device 21.

9. This time relay serves for connection of the two contacts 10 and 11, so that along the lead 12 the current proceeding from the local battery 14 is able to pass via the disc drop 15 indicator board 13 to the releasing coil 15 of the track automatic device 3. The core 16 of this coil is connected in such manner with the track automatic device 3 that upon closing the circuit over the contacts 10, 11 the track 20 automatic device is actuated by the battery 14, whereby the current is cut off from the contact rail. This actuation, according to the invention, is effected from the train itself, or from a block section, and an arrangement 25 is employed such as that shown by way of example in Fig. 2.

Referring to Fig. 2, 17 designates a battery, which may also, in the case of the block section, be replaced by a lighting wire connection. This battery feeds via a switch 18 the electro-motor 19, which by means of the lever mechanism 20 alternately opens and closes the make and break device 21. Upon actuation of the switch 18 the switch 22 is closed, so that the current flows from the contact rail 4 over the lead 23 and the alternately opened and closed make and break device 21 through an adjustable resistance 24 back to the travelling rail 6. By means of this arrangement the sub-station with the dynamo 1 is compelled to supply intermittent D. C., which traverses the travel circuit and possibly superposes the D. C. for running the train. Since the transformer 7, 8 is situated 45 in the circuit the intermittent D. C. traversing the primary coil 7 causes a current to be induced in the coil 8 of the transformer, whereby the current impulses in the coil 8 are maintained for such length of time as the 50 make and break device is in operation. These current impulses cause actuation of the time relay 9, so that after expiry of a certain period, which may be set as desired, the two contacts 10, 11 of the local battery are closed, 55 causing operation of the track automatic device 3. The disc drop indicator board 13 indicates to the operator in the sub-station an intentional release emanating from the track, so that a renewed actuation of the track 60 switch does not take place. Normal switching operations on the track have no influence on the apparatus according to the invention, as these operations do not endure for such length of time as to move the time relay into its extreme position, i.e., to cause the contacts

10 and 11 to be connected. The strength of the intermittent D. C. is somewhere in the neighborhood of 25 amp, as compared with releasing currents of 3,500-5,000 amp, for each automatic device. The same may be applied to practically any desired distance. In 70 place of operation by the electro-motor 19, a hand-operating means with crank or the like may be employed for the make and break device 21.

Fig. 3 shows the connection diagram of an electrically coupled two-rail track. The two parallel tracks comprising the contact rails 4 and the travelling rails 6 are designated by a and b , with adjacent zone a^1 and b^1 coupled by means of the coupling station K and fed by the next sub-station. U^1 and U^2 are the two feed systems of a sub-station for the two different directions of travel. The sub-station for the next zone or section a^1, b^1 is connected in the same manner. In the coupling station, in the same manner as described above in connection with the sub-station, is a transformer consisting of the primary winding 7 and the secondary winding 8. 80 This transformer operates together with the time relay 9 exactly as in the case of the sub-station. The time relay serves for actuation of the three track switches $3^a, 3^b, 3^c$ shown in Fig. 3. These track switches serve the 95 purpose of both connecting the zones a and b , or a^1 and b^1 respectively, i.e., cross coupling, as well as connecting the zones a, a^1 , or b, b^1 respectively, i.e., longitudinal coupling. (The actual reason for this coupling is diminished drop in voltage and better compensation of the load). 100

The operation as regards the diagram of connections shown in Fig. 3 is as follows: It is assumed that a train within the zone a and fed by the contact rail 4 and the travelling rail 6 actuates the device shown in Fig. 2. Since all track switches in the sub-stations and in the coupling stations are closed, the 105 intermittent D. C. flows into the transformers 7, 8 or $7^a, 8^a$ respectively and acts upon the time relay 9, or 9^a respectively. The time relay 9 of a coupling station is, for example, set in such manner that after a period of 5 seconds the same closes the relay current for 110 switching off the track switches $3^a, 3^b, 3^c$, while the time relays 9 in the sub-stations U^1, U^2 do not perform the same operation until after a period of 7 seconds. The result is that in this manner at first the longitudinal and cross 115 coupling of the zones is arrested, viz., above all the zone within which the train is situated will be isolated, i.e., the train causing the sub-station to supply intermittent D. C. Not until then will the appertaining sub-station 120 switch be actuated. In this manner the error will be localized to the zone which requires to be disconnected.

It will be understood that the above description is merely given by way of example, 125

and that various modifications may be made without departing from the spirit of the invention.

What I claim as new and desire to secure by Letters Patent is:

1. In a method of electrically disconnecting at a distance track zones in the case of D. C. railways from a moving train or from a block section, the provision of means where-
5 by actuation as desired of a device provided on the train or at the block section will compel the sub-station to supply intermittent D. C. in the feed circuit, the said intermittent D. C. by the use of a transformer and a time relay
10 serving to actuate one or more automatic devices on the track.

2. In a method of electrically disconnecting at a distance track zones in the case of D. C. railways, from a moving train or from a block
20 section, the provision of a transformer, the primary coil of which is in series with the contact rail, while the secondary coil is connected to a time relay, and automatic devices on the track which, with the assistance of a local bat-
25 tery, are actuated by the said time relay.

3. In a method of electrically disconnecting at a distance track zones in the case of D. C. railways, from a moving train or from a block
30 section, the provision at each coupling station and each sub-station of a transformer and a time relay, which latter actuates the apper-

taining track automatic device and is set in such manner that at first the relay of the coupling station operates for the purpose of interrupting the longitudinal and cross cou- 35 pling, which operation is followed by re-
sponse on the part of the relay which actuates the feed switch of the sub-station pertaining to the particular track zone in question.

4. In a form of embodiment of an arrange- 40 ment for electrically disconnecting at a distance, from a train or block section, track zones in the case of D. C. railway systems wherein the track is divided into zones or sec-
tions, which are coupled together by means of 45 coupling stations and are each fed separately by sub-power stations, a make and break de-
vice on the train or at a block section causing the sub-station pertaining to the zone where-
in the train is located or to which the block 50 section appertains to feed intermittent D. C. into the feed circuit for the train, automatic devices on the track, a transformer at the sub-station having its primary winding in se-
ries with the contact rail and its secondary 55 winding connected to a time relay, and a local battery actuating the said automatic devices, all for the purpose of isolating the particular zone in the case of emergency or requirement.

In testimony whereof I have affixed my sig- 60 nature.

ULRICH KLOSS.
